(57) **CLAIM**

The ornamental design for a panel for computer case, as shown and described.

DESCRIPTION

FIG. 1 is a perspective view of a panel for computer case according to the design, the characteristic feature of which resides in surface ornamentation comprising a geometric cut-out, the figure further illustrating the position of the panel in relation to the computer case;

FIG. 2 is a front view thereof;

FIG. 3 is a right side view thereof;

FIG. 4 is a left side view thereof; and,

FIG. 5 is top view thereof.

The broken lines showing structure are for illustrative purposes only and form no part of the claimed design.
